FOLDING BOX

Murray Kretchmer, New York, N. Y.

Application August 22, 1941, Serial No. 407,920

10 Claims. (Cl. 229—52)

This invention relates to folding boxes.

An object of this invention is to generally improve the type of box shown in my co-pending application Serial No. 355,472, filed September 5, 1940, for *Folding boxes*.

A further object of this invention is to provide a box of the character described, having top cover sections formed with mutually contacting upstanding handles extending substantially all the way across the top of the box, so as to strengthen and rigidify the top of the box, and to prevent the top of the box from being bowed upwardly.

Yet a further object of the present invention is to provide a box of the character described, having a bottom section, end sections extending upwardly from the ends of the bottom section, side sections extending upwardly from the sides of the bottom section, interlocking tabs at one pair of adjacent ends of the end sections located against the inner surface of one of the side sections, a cover section extending from the other side section, and sections extending from the ends of said cover section interconnected to the other pair of adjacent ends of the end sections by hinges.

Yet a further object of this invention is to provide in a box of the character described, a pair of top cover sections having mutually contacting upstanding handles, and having improved means for interlocking the ends of the handles to prevent the handles from separating, and tearing at the points of stress.

Yet a further object of this invention is to provide in a box of the character described having mutually contacting, upstanding handles, a pair of tabs cut from the handles to provide openings for the fingers of the person carrying the box, the tab on one cover section being foldable beneath the other cover section, and the other tab being foldable above the first cover section, and said first cover section being slitted to receive the last mentioned tab.

Yet a further object of this invention is to provide a folding box of the character described, in which one of the cover sections has hooks at the ends thereof adapted to interlock within slits in the end walls of the box, and the other cover section having tabs adapted to overlie the hooks, said tabs being provided with tongues adapted to slip straight downwardly into said slits.

Still a further object of this invention is to provide a box of the character described having top sections provided with mutually contact-

ing, upwardly extending handles, one of the cover sections being formed at the upper ends thereof with flaps extending beyond said cover sections, said flaps being provided with inwardly extending tabs disposed between said flaps and the handle on said cover section, said flaps being adapted to engage the handle on the other cover section, to press the handles together, and said other cover section being formed with slits to receive the end portions of said tabs, to retain said tabs against said cover section, the slits in said other cover section being so positioned and shaped, as to retain said tabs against said handle on said other cover section.

15 Another object of this invention is to provide a strong, compact and durable box of the character described, which may be partially set up and nested in partially set up condition, which shall be easy to completely fold and collapse, which shall be sturdy and rugged and adapted to carry considerable weight, which will not unfold accidentally, which will be highly economical to manufacture, and yet practical and efficient to a high degree.

20 25 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments 30 of this invention,

Fig. 1 is a plan view of a blank from which the box embodying the invention is made;

Fig. 2 is a top perspective view of a box partially set up;

40 Fig. 3 is a perspective view of a box illustrating a further step in setting up the box;

Fig. 4 is a perspective view of a completely set up box;

Fig. 5 is a cross-sectional view taken on line 45 5—5 of Fig. 4;

Fig. 6 is a cross-sectional view taken on line 6—6 of Fig. 5;

Fig. 7 is a top plan view of a blank for making a box embodying the invention, and illustrating a modified form of the invention; and

Fig. 8 is a perspective view of the set up box made from the blank shown in Fig. 7.

Referring now in detail to the drawings, 10 designates a blank for making a box 11 shown in 55 completely set up condition in Fig. 4 of the draw-

ings. The blank 10 comprises a rectangular bottom section 12, forming the bottom wall of the box 11. Extending from the ends of section 12 are similar, symmetrically disposed sections 13 forming the end walls of said box.

The sections 13 are formed with similar, symmetrically disposed slits 13a, each comprising a curved portion 13b, from one end of which there extends an inwardly and then outwardly curved portion 13c, thus forming a depressible tab 13d and a shoulder portion 13e for the purpose hereinafter appearing. Extending from adjacent sides of end sections 13, are mutually interlocking sections 13g and 13h, adapted to extend inwardly toward each other and against the inner face of one of the side walls 14. Said sections 13g and 13h are provided with interlocking hooks 13i and 13j, respectively. The hook 13j extends downwardly from the upper edge of section 13h, whereas hook 13i extends upwardly from a point above the lower end of section 13g, as clearly shown in Fig. 1 of the drawings.

Extending from the sides of section 12 are side sections 14, forming the side walls of the box. Extending from the sections 14 are top cover sections 15 and 16, each having the same length as sections 12, but substantially half the width thereof. The sections 15 and 16 together form the top of the box.

Section 15 is formed adjacent the upper portion thereof with a central slit 17 having a portion 18 parallel to the crease lines 15a and 16a, about which the cover sections fold. The ends of slit portion 18 are curved outwardly, as at 19. Extending from the center of slit portion 18, is a short slit portion 20, extending outwardly in a direction perpendicular to the fold lines 15a and 16a.

Adjacent the ends of section 15 are a pair of similar, symmetrically disposed slits 23, each comprising a portion 24 inclined relative to the fold line 15a. At one end of slit portion 24 is an outwardly extending, short slit portion 25 forming a sharp corner 26 at one end of slit 23. At the other end of slit portion 24, is a short, outwardly curved slit portion 28. At the center of slit portion 24, is a short slit portion 29, extending generally in a direction toward the outer corner of section 15.

Extending from cover section 15 is a handle section 32, preferably extending the full length of cover section 15, and foldable about crease lines 33. Handle section 32 is formed with a pair of spaced, circular finger openings 35. Said handle section is furthermore formed with a slit 36 between the circular openings 35, forming a tab 37 foldable beneath the cover section 16, when the box is set up, as will appear hereinafter.

The tab 37 has a head at its outer end, and a constricted neck portion just beyond its inner end, forming a pair of inwardly extending ears or detents 38 spaced above the fold line 33, for the purpose hereinafter appearing. The ends of the handle 32 may be rounded, as at 40, as illustrated in Fig. 1 of the drawings.

Extending from cover 16 is a handle section 42 having the same width as handle 32, and formed with cut-out circular openings 43, adapted to register with the openings 35. The handle 42 is formed with a central slit 44 producing a tab 45 foldable about the crease line 46, about which the handle folds relative to cover section 16. Tab 45 is insertable through the opening

formed when the tab 37 is pushed beneath cover section 16.

The tab 45 has a constricted neck portion adjacent the fold line 46, and said neck portion is adapted to engage beneath the detents 38 which serve to hold the said tab downwardly on cover section 15. The outer end of tab 45 may be slipped through the slit 17 so that the outer end thereof projects beneath cover section 15. The central slit portion 20 of slit 17 and the slit portions 19 of said slit, facilitate insertion of the tab 45 therethrough.

It will be noted that tab 37 is of less height than tab 45, so that the upper edge of the opening through which the fingers are inserted, formed by slit 36, is at a lower level than the lower edge of the opening formed by the slit 44 of handle 42. The fingers thus engage the handle 32 which bears the major portion of the weight of the box, when the box is carried, as said handle is on the cover section 15, which has portions located beneath the cover sections 16 and is thus held down by cover sections 16, it is preferable to have the major part of the weight carried by the handle 32 rather than the handle 42, since a strong upward pull on the handle 42 might pull up on the cover section 16, and cause said cover section to be bowed upwardly or the ends thereof might tear. This construction takes the stress away from the junctions between the ends of handles 42 and cover section 16.

The ends of handle 42 are symmetrical with respect to one another. At each end is an edge portion 47, spaced inwardly from the outer ends of cover section 16, and perpendicular to the fold line 16a. Extending from each portion 47 is a generally outwardly extending edge portion 48, substantially parallel to fold line 16a. Extending from edge portion 48 is an edge portion 49, generally inclined outwardly and towards section 14. The inclined edge 49 terminates short of the fold line 46, and extending therefrom is an edge 50 parallel to fold line 46 and about $\frac{1}{4}$ " to $\frac{1}{2}$ " in length on ordinary cake boxes. Extending from the outer end of edge 50 is a short edge 50a flush with the upper and lower ends of cover sections 16, and extending to the fold line 46. The handle 42 thus has narrow end portions 51 adjacent the fold line 46.

Extending from the upper and lower ends of cover section 16, are similar, symmetrically disposed sections 60 foldable about fold lines 61, at the ends of sections 16. The width of section 60 is substantially similar to the combined widths of sections 16 and 42. The lengths of sections 60 is however less than the heights of sections 13. The outer edges 62 of sections 60 are thus flush with the outer edge 42a of handle section 42. At the outer corners of section 60, are short tongues 60a, extending straight downwardly when the box is folded and engageable within the slit portions 13b of slits 13a, as shown in Fig. 4 of the drawings.

Extending inwardly from sections 60, are tabs 63 formed by cutting the outer edges of the handle section 42. Thus, the inner edges of tabs 63 are similar to the outer edges of handle 42. When the box is set up, the tabs 63 are adapted to press the handle sections 32 and 42 together. Thus, when the handle 42 is folded upwardly, slots are formed between the bases of the tab 63 and the upwardly extending handles 42, to receive, enclose and engage the outer ends of handle 32 for pressing the handles together, as clear-

ly illustrated in Fig. 4 of the drawings. Furthermore, such construction provides tear stops to prevent tearing of ends of handle 32 along crease lines 80a at the ends of section 15.

The tabs 63 overlie the cover section 15, and the inner ends thereof are inserted through the slits 23, being engaged at the corners 26 formed by said slits, to hold the tabs against the handle 32.

Sections 60 are interconnected to section 13 by similar, symmetrically disposed hinges 70. Each hinge 70 comprises three substantially triangular sections 71, 72 and 73. Section 72 extends from fold line 14a at the end of the side section 14. Section 71 extends from fold line 11a at one side of section 13. Section 73 extends from fold line 60b at one side of section 60. Section 71 is interconnected to section 72 by scored line 74. Section 72 is interconnected to section 73 by scored line 75.

Tab 63 also serves to keep down the cover 14, so that it is not necessary to hook sections 60 to the end walls 13.

When the box is set up, sections 72 fold against the inner surface of the adjacent section 14. Sections 73 fold against the outer surfaces of section 72 and between the sections 72 and 71.

Extending from the ends of cover section 15 are similar, symmetrically disposed hook sections 80 adapted to be folded downwardly against the outer surfaces of sections 13 and passed through the slits 13a for interlocking the shoulders 13e. The tabs 13d may be pressed inwardly to facilitate insertion of the hooks within said slits. The width of the hooks 80 is substantially the same as the combined widths of sections 15 and 32, although it could be less if desired. The height of the hooks is less than the height of sections 13 and is preferably of such height as to contact bottom wall 12 when the box is set up. Said hook sections 80 have hooking heads 81 for engaging the shoulders 13e.

The setting up of box 11 will now be described:

Sections 13g and 13h are first interlocked, bringing the walls 13 upwardly, so that a plurality of boxes may be nested in such partially set up condition. After the sections 13g and 13h are interlocked, the section 14 which carries the cover section 15 is folded upwardly and the hook sections 80 are interlocked within the slits 13a. The tab 37 is then pressed downwardly and the other section 14 is raised, permitting the hinges 70 to fold against the inner surface of said section. Cover section 16 is then brought to the top of the box while sections 60 extend downwardly against the outer sides of the hook sections 80. The tongues 60a are inserted within the slits 13a.

Care should be taken that the tab 37 passes beneath cover section 16. The handles 32 and 42 are brought together in upstanding position, and tab 45 is passed through the opening in handle 32 and interlocked beneath the ears 38. The outer end of tab 45 is then passed through the slit 17. The tabs 63 are then passed around the ends of the handle 32 and engaged within the slits 23.

It will be noted that the handles extend entirely across the box, so as to rigidify the top of the box and to prevent bowing of the top of the box. Furthermore, such construction strengthens the handles themselves. It will now be further understood that the tabs 63 are retained on cover section 15 and held against handle 32 to press said handle against the handle 42.

It will be noted further that the provision of tab 37 prevents weakening of the box by slit 20. The box may be opened by first releasing the tab 45 and the tab 63, so that one side of the box may be opened up substantially to the position shown in Fig. 3 to permit the cake or pie, or other contents of the box to be slidably moved out of the box, without necessity for collapsing the entire box. It will be further understood that the interlocking sections 13g, 13h are at one side of the box only. The combination of the interlocking tabs 13g, 13h with the hinges 70, produce a strong and yet easily set up box.

Furthermore, the fact that only the tabs 80 have to be interlocked within the slits 13a, facilitates setting up the box, since it takes less time to merely pass the tongues 60a through said slits, without necessity for interhooking within said slits.

In Figs. 7 and 8 there is shown a blank 90 for making a box 91 embodying the invention, and illustrating a modified construction usually for smaller boxes. The blank 90 differs from blank 10 in the following manner. Hinged sections 71 of blank 10 are omitted in the blank 90, so that the hinges 70a comprise sections 72a and 73a corresponding to the sections 72 and 73.

Furthermore, the sections 92 of blank 90 which correspond to the sections 60 of blank 10, do not have the tongues 60a, but are merely rounded at their outer corners. Furthermore, in blank 90, the handle openings are wide enough to receive more than two fingers. Thus, the circular openings 45 and 43 are omitted. Said handles are formed with tabs 37a and 45a corresponding to the tabs 37 and 45 of blank 10. The tabs 37a and 45a are however wider than the tabs 37, 45.

Furthermore, in blank 90, the slit 17 is omitted, and instead cover section 94, corresponding to cover section 15, is formed with a pair of similar, symmetrically disposed slits 95 adapted to receive a pair of ears 96 on the ends of tabs 45a.

As shown in the drawings, hooks 100 which correspond to hooks 80 of Fig. 1, are of a width substantially equal to the width of a cover section, and the slits 101, corresponding to slits 13a of Fig. 1, are positioned to receive the heads of said hooks. This construction is for extremely large or extremely small boxes. In large boxes, the bases of the hooks would be too long to fold easily. In small boxes, the width of the hooks must be less than the width of the box.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A box of the character described, comprising a bottom wall, end walls extending upwardly from said bottom wall, side walls extending upwardly from the sides of said bottom wall, means to lock said end walls in upright position, cover sections extending inwardly from said side walls, mutually contacting upstanding handles extending from said cover sections, one of said cover sections being formed with a pair of downwardly extending sections at the ends thereof, hinges

connecting said downwardly extending sections with the other of said side walls, said handles extending substantially entirely across the top of said box, and a pair of tabs on said downwardly extending sections adjacent the ends of one of the handles, adapted to interlock the other of said handles.

2. A box of the character described, comprising a bottom wall, side walls and end walls, said end walls, having slits, a pair of cover sections extending from the side walls and formed with mutually contacting upstanding handles, said handles extending substantially entirely across the top of the box, sections extending from the cover section having tongues received in said slits, and tabs on the section extending from one cover and located adjacent the ends of the handle extending from said cover, forming with said handle, slots receiving the ends of the other handle, said tabs overlying the other cover, said other cover being formed with slits to receive portions of said tabs, said slits being shaped to form edge portions in said other cover to engage edge portions of said tabs and retain said tabs in engagement with said other handle.

3. A box of the character described, comprising a bottom wall, side walls and end walls, a pair of cover sections extending from the side walls and formed with mutually contacting upstanding handles, said handles extending substantially entirely across the top of the box, and tabs connected to sections extending from one cover and located adjacent the ends of the handle extending from said cover, forming with said handle, slots receiving the ends of the other handle, said tabs overlying the other cover, said other cover being formed with slits to receive portions of said tabs, said slits being shaped to form edge portions in said other cover to engage edge portions of said tabs and retain said tabs in engagement with said other handle, said handles being formed with openings to receive the fingers of the person carrying the box, the upper edge of the opening in said other handle extending below the upper edge of the opening in the first handle.

4. A box of the character described, comprising a bottom wall, side walls and end walls, a pair of cover sections extending from the side walls and formed with mutually contacting up-standing handles, said handles extending substantially entirely across the top of the box, and tabs connected to sections extending from one cover and located adjacent the ends of the handle extending from said cover, forming with said handle, slots receiving the ends of the other handle, said tabs overlying the other cover, said other cover being formed with slits to receive portions of said tabs, said slits being shaped to form edge portions in said other cover to engage edge portions of said tabs and retain said tabs in engagement with said other handle, said handles being formed with slits producing tabs adapted to be pushed out of the planes of said handles to form openings in said handles to receive the fingers of the person carrying the box, the tab in the other handle extending beneath the first cover, the tab in the first handle passing through the opening in said other handle, said other handle being formed with a slit to receive a portion of the tab in said first handle.

5. A box of the character described, comprising a bottom wall, side walls and end walls, a pair of cover sections extending from the side walls and formed with mutually contacting up-standing handles, said handles extending sub-

stantially entirely across the top of the box, and tabs connected to sections extending from one cover and located adjacent the ends of the handle extending from said cover, forming with said

5 handle, slots receiving the ends of the other handle, said tabs overlying the other cover, said other cover being formed with slits to receive portions of said tabs, said slits being shaped to form edge portions in said other cover to engage edge portions
10 of said tabs and retain said tabs in engagement with said other handle, said handles being formed with slits producing tabs adapted to be pushed out of the planes of said handles to form openings in said handles to receive the fingers
15 of the person carrying the box, the tab in the other handle extending beneath the first cover, the tab in the first handle passing through the opening in said other handle, said other handle being formed with a slit to receive a portion of
20 the tab in said first handle, the upper edge of the opening in said other handle extending below the upper edge of the opening in the first handle.

6. A box of the character described, comprising a bottom wall, end walls extending upwardly from said bottom wall, side walls extending upwardly from the sides of said bottom wall, one pair of adjacent ends of said end walls being provided with interlocking tabs adapted to lie against the inner face of one of said side walls, cover sections extending inwardly from said side walls, mutually contacting upstanding handles extending from said cover sections, one of said cover sections being formed with a pair of downwardly extending sections at the ends thereof, hinges connecting said downwardly extending sections with the other pair of adjacent ends of said end walls, and adapted to fold against the inner face of the other of said side walls, said handles extending substantially entirely across the top of said box, and a pair of tabs on said downwardly extending sections adjacent the ends of one of the handles, adapted to interlock the other of said handles, said tabs overlying said other cover, said other cover being formed with slits to receive portions of said tabs, a pair of hooks at the ends of said other cover, said end walls being formed with slits to receive said hooks.

7. A box of the character described, comprising a bottom wall, end walls extending upwardly from said bottom wall, side walls extending upwardly from the sides of said bottom wall, one pair of adjacent ends of said end walls being provided with interlocking tabs adapted to lie against the inner face of one of said side walls, 55 cover sections extending inwardly from said side walls, mutually contacting upstanding handles extending from said cover sections, one of said cover sections being formed with a pair of downwardly extending sections at the ends thereof, 60 hinges connecting said downwardly extending sections with the other pair of adjacent ends of said end walls, and adapted to fold against the inner face of the other of said side walls, said handles extending substantially entirely across the top of said box, and a pair of tabs on said 65 downwardly extending sections adjacent the ends of one of the handles, adapted to interlock the other of said handles, said tabs overlying said other cover, said other cover being formed with slits to receive portions of said tabs, a pair of 70 hooks at the ends of said other cover, said end walls being formed with slits to receive said hooks, said downwardly extending sections being formed with tongues adapted to pass straight 75 down through said slits in said end walls.

8. A box of the character described, comprising a bottom wall, side walls and end walls, said end walls being slit, a pair of cover sections extending from the side walls and formed with mutually contacting, upstanding handles, said handles extending substantially entirely across the top of the box, a pair of sections extending from the ends of one of the cover sections, said pair of sections having tongues to engage in said slits in said end walls, and tabs on said pair of sections forming slots with said cover sections to receive the ends of the handle on the other cover section, said other cover section having slits to receive said tabs.

9. A folding box comprising a bottom wall, side walls and end walls, a pair of cover sections extending from the side walls and formed with mutually contacting upstanding handles, said handles extending substantially entirely across the top of the box, each of the handles being formed with a central opening and two openings on opposite sides of the central opening, the openings in one handle registering with the openings in the other handle, a tab on one cover section passing through the central opening in the handle which extends from the other cover section, a pair of hook sections extending from the ends of one cover section, said end walls being formed with slits, each of the slits comprising a bottom curved portion, a portion extending inwardly from one end of the curved portion, and a portion extending upwardly from one end of the inwardly extending portion, said hook sections each having a hook portion adapted to be passed through one of the slits, said slits forming in the end walls, portions which may be pressed inwardly to facilitate

insertion of the hooks through the slits, said hooks being adapted to engage portions of the end walls formed at the junction of the curved portions of the slits and the inwardly extending portions of the slits.

10. A folding box comprising a bottom wall, side walls and end walls, a pair of cover sections extending from the side walls and formed with mutually contacting upstanding handles, said handles extending substantially entirely across the top of the box, each of the handles being formed with a central opening and two openings on opposite sides of the central opening, the openings in one handle registering with the openings in the other handle, a tab on one cover section passing through the central opening in the handle which extends from the other cover section, a pair of hook sections extending from the ends of one cover section, said end walls being formed with slits, each of the slits comprising a bottom curved portion, a portion extending inwardly from one end of the curved portion, and a portion extending upwardly from one end of the inwardly extending portion, said hook sections each having a hook portion adapted to be passed through one of the slits, said slits forming in the end walls, portions which may be pressed inwardly to facilitate insertion of the hooks through the slits, said hooks being adapted to engage portions of the end walls formed at the junction of the curved portions of the slits and the inwardly extending portions of the slits, said central openings being sufficiently wide to receive two fingers, and the openings on opposite sides of the central opening being adapted to receive one finger of a person carrying the box.

MURRAY KRETCHMER.
